L. STEIN

TEMPORARY BINDER

Filed Sept. 12, 1921

Inventor
Louis Stein
By Miller, Chindell & Parker
Attns

UNITED STATES PATENT OFFICE.

LOUIS STEIN, OF CHICAGO, ILLINOIS.

TEMPORARY BINDER.

Application filed September 12, 1921. Serial No. 500,043.

To all whom it may concern:

Be it known that I, LOUIS STEIN, a citizen of the United States, residing at Chicago, in the county of Cook and State of Illinois, 5 have invented certain new and useful Improvements in Temporary Binders, of which the following is a specification.

This invention relates to the class of temporary binders in which the cover, or covers, 10 and the contained sheets are secured together by means of a cord or other flexible element.

The object of the invention is to provide in such a binder simple and convenient means for securing the cord or cords in place 15 after they have been drawn taut; and to make the securing devices of minimum thickness in order that it shall be practicable to dispose them inside the binder rather than upon the exterior thereof.

20 In the accompanying drawings, Figures 1 and 2 are perspective views of the binder showing the manner in which the cord is arranged. Fig. 3 is a sectional view taken in the plane of dotted line 3—3 of Fig. 4. Fig. 25 4 is a section on line 4—4 of Fig. 3. Fig. 5 is an enlarged fragmentary view taken in the plane of line 5—5 of Fig. 4. Fig. 6 is a perspective view of one set of the securing devices.

30 The embodiment herein shown of the invention comprises two covers 1 connected by a flexible back 2. Two binding strips 3 and 4 are attached to the inner side of the back 2. The binding strips 3 and 4 and the leaves 35 intended to be held in the binder are suitably perforated for the passage therethrough of a cord 5. In this instance there are two holes 6 near the middle of the binding strip 4, through which holes the middle portion of 40 the cord 5 extends. Near the ends of the binding strip 4 are holes defined by eyelets 7 through which the cord 5 passes. The leaves are provided with circular perforations 8 (Fig. 5) which register with the eyelets 7.

45 The binding strip 3 is provided with openings that register with the perforations 8. Preferably the openings in the binding strip 3 are reinforced by means of eyelets 9. Attached to the binding strip 3 is an element 50 adapted to enter the eyelet 9 and bind or clamp the cord 5 therein. In the present construction, I provide a base 10 having a perforation through which the eyelet 9 extends, said eyelet serving to secure the base 55 10 firmly to the binding strip 3. A cap 11 is pivoted to the base 10 at 12. On the inner or

lower side of the cap 11 is a stud 13 adapted to enter the eyelet 9 and clamp the cord 5 between itself and said eyelet, as shown in Fig. 5. Preferably the cap 11 is larger than the base 10, the edges of the cap 11 being bent downwardly so as to enclose the base. The caps 11 are hinged at the outer side of the bases 10 (having reference to the ends of the binding strip), said caps, therefore, swinging toward each other as they move into closed position. Those portions of the caps which extend toward the center of the binding strip are bent to form a recess 14, (Fig. 6), in which the cord 5 may lie.

70 It will be seen that after the cord 5 has been passed through the leaves and through the eyelets 9, one end of the cord may be pulled to draw the binding strips 3 and 4 and the leaves together at that end of the binder, whereupon the adjacent cap 11 may be swung down to clamp the cord between the stud 13 and the eyelet 9. Traction may then be exerted upon the other end of the cord to draw the cord taut, after which the other cap 11 may be swung down to clamp the cord.

75 In opening the binder the caps may be raised by gripping them with the fingernail in the recesses 14 or, more easily still, by 80 pulling upwardly on the free ends of the cord against the caps to cause them to open. This can be done with one hand by holding the free ends of the cord together and pulling them. The manner in which the leverage 85 is applied to open the caps in this way seems obvious in Fig. 5.

90 Since the fastening devices 9 and 11 are comparatively thin and flat, it is practicable to employ them inside the binder, as shown, 95 as they cause no objectionable bulging, or space between the leaves and the cover.

99 The perforations in the leaves are simply round holes which may be readily punched with tools in common use.

100 I would have it understood that the elements herein disclosed may be employed in various arrangements without departing from the scope of the invention as set forth in the appended claims.

105 I claim as my invention:

110 1. A temporary binder having, in combination, two covers, two binding strips suitably related to said covers, one of said strips having openings, a cord extending through said openings, the other strip having eyelets registering with said openings, caps movably

attached by the eyelets to the last mentioned binding strip and swingable on a horizontal axis alongside the eyelets over the same, and a stud on each cap adapted to enter the eyelet and clamp the cord therein.

2. The combination in a temporary binder, of a pair of covers arranged for extension from one another to receive fillers of different thicknesses, one of said covers having an opening, a cord extended therethrough to hold the covers together, any portion of the length of said cord being extended through said opening depending upon the size of filler between the covers, and a clamping member having a portion arranged to be pressed into said opening to clamp the portion of the cord extending therethrough, said member being formed to permit the undoing thereof simply by pulling upon the cord.

3. In a temporary binder, a binding element having an opening therethrough, a base on said element, an eyelet located in said opening and serving to secure the base to the binding element, a cap hinged to the base, and a stud on the cap adapted to enter the eyelet.

4. In a temporary binder, a binding element having an eyelet, a cord passing through the eyelet, a cap pivoted to the binding element, and a stud on said cap adapted to enter the eyelet and clamp the cord therein, said cap substantially enclosing the eyelet and having a recess to accommodate the cord.

5. In a temporary binder, a binding element having an eyelet, a cord passing through the eyelet, a part pivoted with respect to the binding element and held rigidly thereon by said eyelet, and a stud on said part adapted to enter the eyelet and clamp the cord therein.

6. In a temporary binder, a binding element having an eyelet, a cord passing through the eyelet and arranged to lie against the face of the binding element, and a part having a projection for holding the cord in the eyelet and having a recess terminating in slightly spaced relation to the projection to receive a portion of the length of the cord beneath the part when the same is in holding position.

7. In a temporary binder, a binding element having a pair of spaced eyelets, a cord having free ends passing through said eyelets and arranged to extend toward each other lying against the face of the binding element, and lever-like members pivoted

alongside the eyelets to swing toward each other over the eyelets, said members having projections thereon for clamping the cord in the eyelets and having portions adjacent the projections to overlie portions of the length of the cord when the members are in holding position.

8. In a temporary binder, a binding element having an eyelet, a cord passing through the eyelet, a lever-like cap for the eyelet pivotally mounted adjacent the same to swing over the same, said cap having a stud projecting therefrom to be received in the eyelet, the stud having an enlarged rounded end arranged upon pressure being applied to the cap to clamp the cord between it and the side of the eyelet to hold the cord.

9. In a temporary binder, the combination of two covers, one having free cord ends extending therefrom in spaced relation and the other having spaced eyelets to receive the cords, and lever-like clamping elements on the last mentioned cover pivotally attached thereto to swing over the eyelets toward each other to clamp the free cord ends in the eyelets, the said cord ends being arranged to extend toward each other lying against the face of the cover and said clamping elements being arranged upon a pull on the cord ends to swing to an open position free of the cord ends.

10. The combination in a temporary binder of a pair of covers arranged for relative adjustment to include fillers of varying thicknesses, the one of said covers having a flexible cord extending therefrom and the other of said covers having an eyelet through which the cord is arranged to pass, and a clamping member swingably attached to the last mentioned cover alongside the eyelet arranged to clamp the cord in the eyelet, said clamping member being conformed and arranged to clamp the cord in such a way that it may be opened by a pull upon the cord.

11. In a temporary binder, a cover having an opening, a flexible cord to extend through said opening, an eyelet for said opening, and means for clamping the cord in said eyelet comprising a base held by the eyelet flat upon the cover, a cap having a pivoting portion held between the base and cover, and means on the cap adapted to engage the cord to clamp the same in the opening.

In testimony whereof, I have hereunto set my hand.

LOUIS STEIN.
